METHOD AND MEANS FOR SURFACING
ROADS

John N. Heitzel, Warren, Ohio

Application May 28, 1930. Serial No. 456,556

20 Claims. (Cl. 94—39)

The present invention relates to machines for use in building roads of concrete or the like and in operation upon the concrete when in a plastic state, and also for use in the surfacing of road 5 structures.

An object of the present invention is to provide an improved joint producing apparatus and method of operating the same, and to provide novel means and ways of finishing the concrete 10 on opposite sides of the joint which is produced.

Another object of the present invention is to provide an improved means for producing a longitudinal central joint in a roadway and means for maintaining the joint producing means in 15 proper alignment with respect to the laterally disposed forms and without reference to any inequality which may be inherent in the structure and incident to the operation of the carriage or frame of the machine.

20 The invention still further aims at the provision of an improved cutter and mounting therefor adapted for vertical adjustment from the frame or carriage and which may be quickly and easily swung into and out of position for 25 carrying on the various steps of the operation in forming and treating the plastic concrete surfacing structure.

A further object of the present invention is 30 to provide a novel construction of compacting tools or means for operation upon the surface of the roadway at opposite sides of the joint or seam which is formed and which may be operable immediately behind the blade or simultaneously at opposite sides thereof, and which is 35 adjustable with reference to the blade itself so as to at all times maintain the proper levelling of the surface at opposite sides of the joint.

With the foregoing and other objects in view, which will be apparent as the description proceeds, the invention resides in the construction and arrangement of parts as hereinafter described and claimed, it being understood that changes can be made within the scope of what is claimed, without departing from the spirit 45 of the invention.

The invention is illustrated in the accompanying drawings, wherein—

Figure 1 is a fragmentary perspective view 50 of a joint producing apparatus as applied to the surface of a roadway, the dotted lines showing the forming blade in raised position out of the way.

Fig. 2 is a fragmentary enlarged transverse section through the forward portion of the apparatus, showing the cutting tool and mounting 55

therefor as disposed with reference to the surface portion of the roadway and the side form therefor.

Fig. 3 is a similar view but showing a modified construction of cutting implement and guide and 60 mounting therefor.

Fig. 4 is a detail enlarged perspective view 65 of a modified form of compacting implement or tool as applied to the forming blade and shown with reference to the surface of the roadway.

Fig. 5 is a detail perspective view of a further modified form of compacting implement or tool as applied to the blade, and showing the method of impressing aggregate into the surface of the 70 roadway at opposite sides of the joint.

Fig. 6 is a fragmentary perspective view 75 showing in detail the adjustable mounting of the forming blade partially removed from the joint slot of the roadway, and showing a permanent joint strip mounted in a prior formed portion of the joint slot, and

Fig. 7 is a detail perspective view, enlarged, 80 of one of the side forms for the surface portion of the roadway and showing a guiding flanged wheel applied thereto.

Referring now to the drawings, and first with particular reference to Figs. 1 and 2, 15 designates a plastic concrete slab in which is engaged a cutting implement, such as the disk 16 mounted upon a transversely extending shaft 17 85 mounted at opposite ends between pairs of rollers 18 disposed in the lower ends of arms 19 which slidably fit through frame member 20 forming part of the carriage or frame of the main road surfacing machine. These arms 19 90 have handles 21 upon their upper ends by means of which the arms 19 may be raised and lowered so as to properly adjust the cutting disk 16. The upper end portions of the arms 19 are provided with openings 22 therethrough adapted 95 to receive pins or the like for adjustably holding the arms 19 in vertically adjusted positions through the frame member 20. One of the arms 19 may be provided thereabout with a tension spring 23, shown in Fig. 2, which is adapted to 100 normally urge the adjacent arm 19 downwardly under sufficient pressure to hold a gage wheel 24, mounted on the adjacent ends of the shaft 17, against the top of a side rail or track 25 extending along one lateral portion of the concrete slab 15. The arm supporting the cutting disc may be provided with spring 23—A to transmit pressure to the disc and will also relieve the apparatus of strains caused by the disc when 105 rolling over steel dowel bars.

110

The cutter 16 engages in the plastic mass and deflects to opposite sides stones, and other large particles which are found in the mass and also divides the mass to provide a division slot 26 of the desired depth. In order to maintain, shape and preserve the slot in the desired size until the material has sufficiently set, a shaping blade 27 is provided. This shaping or forming blade 27 is of desired length, is arranged vertically in edgewise relation and in alignment with the disk 16, and is preferably rounded downwardly and rearwardly at the forward end as shown to advantage in Fig. 1 so that the blade 27 may closely follow the cutting disk 15 and engage in the slot 26 so as to spread the walls thereof and maintain the walls in properly spaced apart relation until the plastic material sets sufficiently to maintain the slot 26 at the desired width and depth. In order to effect this relatively quick setting of the material after the blade 27 has been inserted in the slot 26, the plastic mass may have admixed therein the desired quantity of calcium chloride which produces a quick set in the concrete.

The forward end of the blade 27 is provided with an upstanding shank 28 which is mounted by means of a pivot 29 upon the lower end of a standard 30 which is suitably mounted upon the frame or carriage of the machine so as to maintain the blade 27 at the desired depth in the slot 26. It will be noted that the shank 28 is of sufficient length so that when the blade 27 is swung into raised position, as shown in dotted lines in Fig. 1, the blade 27 will clear the upper surface portion of the slab 15 and will permit of easy access to the opposite sides or edge portions of the slot 26 for subsequent treatment, such as compacting or the like. To facilitate the raising and lowering of the blade 27 the latter is provided at its upper edge and near its rear end with a handle 31, and the blade is also apertured adjacent to the handle for receiving therethrough a pin 32 for connecting the handle to the lower end of an arm 33 which is vertically and slidably mounted in a portion of the carriage frame 20, as clearly shown in Fig. 1, the arm 33 being adjustably held in position by means of a peg 34 adjustably engaging in openings or the like formed in the arm 33 as shown.

The blade 27 is provided with an edging tool 35 in the form of a relatively flat plate adapted to extend across the slot 26 and overlap upon the plastic material at opposite sides of the slot, as shown in Fig. 1. This edging tool 35 is provided with a depending web 36 which merges into the lower side of the plate 35 and is rounded at the point of merging to conform with the rounded configuration desired for the opposite upper edges of the slot 26. This plate 35 is carried upon the rear end of an arm 37 which is pivotally mounted upon the pivot 32 near the forward end of the arm 37, and said forward end of the arm 37 is provided with a threaded eye 38 through which a threaded screw 39 is carried, the lower end of the screw 39 abutting against said lug 40 which projects from one side of the blade 27 so that by turning the screw 39 downwardly the lower end of the arm 37 is depressed. The upper end of the screw 39 may be provided with suitable hand holds or the like of any suitable configuration to facilitate the turning of the screw 39. Thus the desired pressure of the edging tool may be obtained by adjustment of the screw 39.

It may be found necessary in cases of unfavorable weather conditions, particularly during rainy weather, to protect the open joint or slot 26 against damage, and to provide for this condition, a flexible strip 41 which may comprise rubber or other suitable material, is mounted upon a reel 42 carried by the frame 20 in such position that the strip 41 may be payed out from the rear end portion of the machine as the latter moves forwardly, the strip 41 being of sufficient width to adequately cover the slot 26, as shown in Fig. 1. After the strip 41 has served its purpose it may be reclaimed and rewound upon the spool 42 for subsequent use. A rubber tubular member 41-A may be used in lieu of the strip 41.

The guide wheel 24 is provided with collars and set screws at opposite sides for securing the guide wheel upon the shafts 17, and the cutting disk 16 is also provided with collars and set screws, as shown in Fig. 4, for securing the same in desired longitudinal relation upon the shaft 17. The shaft 17 is preferably made in two parts arranged in telescoping relation and adjustably secured together by means of a set screw 43 so that the cutting disk 16 may be disposed in properly spaced relation from the guide wheel 24 dependent upon the width of the section of the slab 15 which is to be included between the edge portion of the slab and the slot 26.

Referring now to Fig. 3, showing a modification of the guide member and the cutting member disclosed in Fig. 2, a frame or supporting bar 44 is carried transversely on the carriage or machine and is provided with a pair of spaced socket members 45 and 46 adjustably held upon the frame member 44 by set screws 47. The socket 46 receives therein the ball head 48 of a guide member 49 of preferably hollow construction and provided with spaced walls the lower ends of which are free and unobstructed and adapted to engage over the upper flange of the side guide rail 25. A channel iron 50 or the like is welded or otherwise suitably secured between the side walls of the guide member 49 in spaced relation to the lower edge portions thereof and is adapted to seat flat upon the upper face of the rail 25 for holding the guide member 49 in proper position thereon. A spacing rod 51 engages slidably through the intermediate portion of the guide member 49 and is adjustably held in fixed relation thereto by means of a set screw 52 threaded downwardly to the top of the guide member 49 as shown in Fig. 3. The spacing rod 51 extends transversely over the slab or upper surface of the roadway 15 and its inner end is slidably connected upon a cutting member 53. The cutting member 53 comprises a relatively flat plate adapted to move over the upper surface of the slab 15 in desired spaced relation above the same and which is provided at its forward end with an upwardly inclined shank 54 terminating in a ball head adapted for engagement in the socket 45. The plate 53 is provided with a pair of upstanding flanges 55 having vertically disposed slots 56 therein for the reception of the adjacent end of the spacing rod 51 and for the purpose of permitting the rise and fall of the cutting member on the rod 51. The rod 51 is provided at the outer sides of the flanges 55 with stop collars 57 to hold the cutting member against lateral movement upon the rod 51. The under side of the plate 53 is provided with a depending vertically disposed blade 58 which is

curved upwardly and forwardly at its ends and adapted to engage in the plastic mass for forming or cutting the groove therein. The blade 58 is adapted to take the place of the disk 16 as shown in Fig. 2.

The plate 53 of the cutting member is provided at its rear end portion with an upstanding lug 59 to which is pivotally connected the lower end of a connecting arm 60 having an eccentric strap 61 on its upper end encircling an eccentric 62 mounted upon a shaft 63 adapted to be turned by the mechanism of the machine for raising and lowering the cutting element and vibrating the same so as to insure a cutting action of the blade 58 in the plastic material. During operation of the eccentric 62 the cutting element is thus raised and lowered at its rear end so as to insure the proper cutting of the blade 58 through the material, the separation of the pebbles and other particles contained in the plastic mass and the proper formation of the groove 26. The sockets 45 and 46 provide for the transverse vibrations or shiftings of the main frame or carriage of the machine without disturbing the relation between the guide member 49 and the cutting member 53.

For use in conjunction with the forming blade 27, there is shown in Fig. 4 a novel construction of float. The float comprises a pair of spaced plates or boards 64 which are arranged horizontally at opposite sides of the blade 27 and are connected together by means of transversely disposed brackets 65 which are of spring steel, providing means to open and close the blades, arched upwardly intermediate their ends so as to pass in spaced relation over the upper edge portion of the blade 27. The intermediate portions of the brackets 65 are provided with upstanding webs 66 which are connected together by an intermediate bar 67 which provides a handle or connecting means by means of which the float may be operated or manipulated.

Each bracket 65 is provided at one side with a pair of vertically disposed and vertically slotted ears 68 adapted to receive the opposite ends of a roller 69 therein. The ears 68 carry a vertically slidable bearing 70 therebetween, the bearing 70 extending across the upper portion of the roller 69 and engaging the opposite ends thereof for the purpose of raising and lowering the roller 69 upon the vertical adjustment of the bearing 70 between the ears 68. Each bracket 65 is also provided, at a point between and above the ears 68 with an outstanding lug 71 through which is threaded an adjusting screw 72 having a hand wheel or the like upon its upper end adapted to be turned for moving the bearing 70 downwardly and pressing the roller 69 against the upper edge portion of the blade 27. This adjustment provides for the easy sliding movement of the float along the blade 27 and also admits of the vertical adjustment of the float with reference to the blade so as to properly even off the upper surface of the slab 15 at opposite sides of the longitudinal slot 26.

From Fig. 4 it will be noted that the inner edge of each board 64 is provided with a depending tapering flange 73 adapted to engage in the upper portion of the groove 26 and to round off the edge thereof to the desired configuration. Also, the forward edges of the board 64 are beveled or inclined and flare outwardly and forwardly with respect to each other as clearly shown in Fig. 4 and for the purpose of

rolling inwardly the excess material accumulating against the forward edges of the board. The rollers 69 will therefore operate not only as gauges, but also will prevent unnecessary friction and wear between the tool and the forming blade 27. Both ends of 64 may be bevelled.

In use, this floating tool will be reciprocated longitudinally on the blade 27 progressively as the blade is drawn through the plastic concrete or, the carriage or frame of the machine may be brought to a standstill and the float operated lengthwise of the blade 27 while the machine is at rest. The forwardly outwardly flaring ends of the boards 64 force the surplus plastic concrete toward the longitudinal blade 27 as the float is drawn lengthwise of the blade.

Referring now to Fig. 5, there is shown a modification in the construction of float or presser for cooperation with the blade 27. In this instance, the device comprises a pair of rolls 74 which are mounted upon a transverse shaft 75 and positioned in spaced apart relation for receiving the upper edge portion of the blade 27 therebetween. The shaft 75 is provided, between the rolls 74, with a supporting or gauge roller 76 which is relatively small and adapted to ride along the upper edge of the blade 27. The diameter of the gauge roller 76 determines the extent to which the side rollers 74 project downwardly from the upper edge of the blade 27 so as to engage the upper surface portion of the slab 15 while the latter is in a semi-plastic condition.

The rollers 74 are operated on the opposite side 110 of the longitudinally disposed blade 27. In some of the earlier methods of installing mechanical joints, it has been found that a surplus of water accumulates along the line of the joint. In some localities engineers consider 115 this an objectionable feature. It has been found impossible however to avoid the mortar joint entirely. Therefore, in order to produce a homogeneous structure throughout the cross section of the slab, it has been found desirable to 120 add stone, gravel or other suitable coarse aggregate to be compacted along the joint to produce denser concrete therat, or in other words, reinforce or armor the road slab longitudinally 125 on both sides of the joint or slot 26. In Fig. 5 the coarse aggregate 77 is shown as being placed or spread along the upper surface of the slab 15 against the opposite side of the blade 27 and in position to be pressed by the rolls 74 into the 130 surface portion of the plastic material. After a sufficient quantity of this coarse aggregate 77 has been delivered on each side of the blade, the rollers 74 are brought into play to compact or depress the aggregate 77 and work the aggregate into the plastic material to produce a sort of bond. It may be desirable to use a mechanical tamping method instead of the rollers 74, but the latter are preferable because the product is even and smooth and the rollers 74 may be 135 manipulated at a much greater speed.

In Fig. 6 is illustrated the method of using the blade 27 when it is desired to install pre-molded joints. The blade 27 is positioned in the concrete slab 15, the blade being supported in 140 position from the traveling bridge or other portion of the carriage or frame by the depending arm 19 at one end and the depending arm 33 at its rear end. These arms 19 and 33, as disclosed in connection with Figs. 1 and 2, are vertically 145

adjustable so that the blade 27 may be adjusted to various heights. After the concrete has been compacted and finished on each side of the blade 27, the blade is raised out of position by the hand grip 31, and is swung entirely clear of the slot 26, as shown in dotted lines in Fig. 1. While the blade 27 is in this raised position the premolded, or other suitably formed joint strip 78 is inserted in the slot to be left permanently therein if desired. The strip 78 may be in the nature of a removable joint strip which later may be removed and then the joint poured with suitable material. The strip 78 serves to maintain the groove or slot in proper shape during the setting of the material. The carriage or frame 20 is then moved forward so that the free end of the blade 27 clears the forward end of the joint strip 78 when the blade 27 is then moved down into the concrete either by gravity or by suitable forcing means which may be applied so that the blade 27 will extend down into the plastic mass to the desired depth. The operation is repeated by compacting the material along the joint, and in this method of operation the blade is not drawn longitudinally through the plastic concrete.

Referring now to Fig. 7, there is disclosed a modified construction of road form or side rail which is disposed along one side of the plastic slab 15 to hold the same in form while setting. As shown, the form comprises a lower road rail 79 having a relatively wide lower or base portion which extends outwardly and is adapted to seat on the sub-base to line and grade and staked in position by the stakes 80 which extend downwardly through sockets 81 which are carried in diagonal brace plates 82 which extend between the outer upturned portions of the base plate and the upper downturned edge of the rail 79. The lower rail 79 is provided with a top rail 83 which is provided with a horizontal tread portion at its top and a depending web portion 84 at its inner edge adapted to lap against the inner side of the rail 79 and slide thereon for vertically adjusting the top rail 83.

A desired number of vertical supports in the form of posts 85 are disposed vertically through the top and bottom flanges of the lower rail 79 and project downwardly into the sub-base of the roadway. The upper ends of the posts 85 project beyond the top of the rail 79 and are adapted to engage beneath the tread portion of the upper rail 83 to support the same in elevated position. Each post 85 is provided with a vertical slot 86 which is arranged to extend above and below the upper portion of the rail 79 and which is adapted to receive therethrough a wedge shaped key 87 which rests at its lower edge upon the upper surface portion of the lower rail 79 and which is adapted at its upper edge to engage the upper end of the slot 86 so as to support the posts 85 at the desired elevation and to thus support the top rail 83 at the desired height. The upper portion of the top rail 83 is of suitable width to hold and guide thereon the carriage wheel 88 which is mounted on the shaft 89 of the frame or carriage.

It is of course understood that various changes and modifications may be made in the details of construction and design of the above specifically described apparatus and also in the various steps of the method described in connection with the use of the apparatus without departing from the spirit of this invention, such changes and

modifications being restricted only by the scope of the following claims.

Having thus described the invention, what is claimed as new is:

1. A joint producing apparatus, consisting of a movable frame over a plastic concrete surfacing structure, a longitudinal blade to be forced into the plastic concrete, the top of said blade projecting above the top surface of the concrete, and means for finishing the concrete movable longitudinally on each side of the blade independently of the blade. 80 85

2. A joint cutting and installing apparatus, consisting of a movable carriage over the roadway under construction, a cutting blade suspended from the carriage to separate the coarse aggregate in the line of the joint, a joint producing blade to be dropped into the incision produced by the first named blade, and means for compacting and smoothing the material along 90 95 the joint producing blade while the latter blade is in stationary position in the groove.

3. A method of producing joints in concrete roads, consisting of pouring the concrete, subsequently slotting the concrete with a rigid blade, 100 supplying a quantity of stone or other suitable coarse aggregate longitudinally along each side of the blade, compacting and working the said gravel into the plastic concrete to produce a denser structure and finishing the surface of 105 the concrete on both sides of the blade, removing the blade from the groove and inserting joint material in the groove.

4. A joint producing apparatus for a plastic concrete surfacing structure, comprising a frame, 110 a cutting member carried by the frame and adapted to engage in the plastic concrete surface for cutting a groove therein, a forming blade carried by said frame in rear of and in line with said cutting member adapted to form 115 and shape the groove after being cut, and an edging device mounted upon the rear end of said blade and arranged for adjustment with respect thereto for engaging the edge portions of the groove formed by the cutting device and the 120 blade for shaping and compacting the edge portions of the groove.

5. A joint producing apparatus of the character described, comprising a frame, a cutting disk mounted in the forward end of the frame 125 adapted to engage in the upper surface of a plastic slab for cutting a groove therein, a blade mounted on said frame in rear of and in line with said cutting disk, means for depressing said blade into the slot in said slab 130 formed by said cutting disk for shaping the slot, an adjustable arm mounted upon the rear end of said blade, means for adjusting said arm to raise and lower the rear end thereof, and a combined edging and pressing member 135 mounted upon the rear end of said arm adapted for engagement with the edge portions of said slot in the slab.

6. In joint producing apparatus for plastic concrete surfacing structures, comprising a forming blade adapted to engage in the upper surface of the concrete structure to form a slot therein, a pair of boards arranged at opposite sides of said blade, brackets connecting said boards and arched upwardly over said blade, 145 rollers carried by said brackets adapted to engage the upper edge portion of said blade for supporting the boards thereon and admitting of the free and easy reciprocation of the boards lengthwise of the blade and supported there- 150

- from, and means carried by the brackets and engaging the rollers for vertically adjusting the same to raise and lower the boards with respect to the upper edge portion of the blade.
- 5 7. A joint producing apparatus, a vertical arm, a forming blade pivotally mounted at its forward end to the lower end of said arm and adapted to be swung downwardly thereon for engagement in the upper surface of a concrete structure for forming a slot therein, a second vertical arm spaced rearwardly from said first arm, and means for detachably securing the rear end portion of said blade to said second arm for holding the blade at the desired depth in the concrete structure, said blade having a hand hold at its upper edge and adjacent its rear end portion for swinging said blade into and out of operative position.
- 10 8. A joint cutting and installing apparatus consisting of a carriage movable over the roadway under construction, a blade on the carriage adapted to be inserted in the concrete, and means for compacting and smoothing the material along the blade while the blade is in stationary position in the concrete.
- 15 9. A joint cutting and installing apparatus consisting of a carriage movable over the roadway under construction, a blade supported on a carriage adapted to penetrate the concrete, and means movable along and guided by the blade while the latter is stationary for compacting and smoothing the material at opposite sides of the blade.
- 20 10. A joint cutting and installing apparatus consisting of a carriage movable over the roadway, a blade suspended from the carriage for partially penetrating the concrete, and means lying on both sides of said blade and having a rolling motion up and down upon the blade for compacting and smoothing the concrete material along the line of the joint.
- 25 11. A joint cutting and installing apparatus consisting of a carriage movable over the roadway, a blade on the carriage for partially penetrating the concrete, means mounted to roll back and forth on said blade and having portions extending on both sides of said blade for engaging the concrete to compact and smooth the same along the line of the joint, and adjusting means for varying the vertical position of said last named means.
- 30 12. The herein-described method for installing joints in plastic surfacing structures, which consists in moving a blade in plastic concrete, and smoothing the material along the line of the joint while the blade is in position.
- 35 13. The herein-described method for producing joints in plastic surfacing structures, which consists in moving the blade in plastic concrete, and compacting and smoothing the surface of the concrete material at opposite sides of said blade by motion back and forth guided by the blade while the blade is in a stationary position.
- 40 14. The herein-described method for producing joints in plastic surfacing structures which consists in initially cleaving the concrete, reforming the cleft, subsequently edging said cleft while smoothing the side surfaces of the same, and trailing protective strip in the cleft.
- 45 15. A joint cutting apparatus comprising a carriage, and concrete cleaving means loosely connected to the carriage to permit the carriage to shift laterally without imparting a like movement to the blade.
- 50 16. A joint cutting apparatus comprising a carriage, concrete cutting means swivelly connected to the carriage, and guide means traveling on the side form and also swivelly connected to the carriage.
- 55 17. A joint cutting apparatus comprising a carriage, concrete cutting means swivelly connected to the carriage and adjustable laterally of the carriage, and guide means traveling on the side form swivelly connected to the carriage and adjustable laterally of the carriage.
- 60 18. The method of forming joints in plastic concrete of a road under construction, consisting in pouring and surfacing the plastic material, containing coarse and fine aggregates, causing a separation of the coarse aggregate along the line of proposed joint to cause a zone of mortar to accumulate, consisting of the finer aggregates, and thereafter moving a member in said zone and depositing additional coarse aggregates along the member and agitating the coarse and fine aggregate to cause a mixture and bond of all material within the zone to produce a dense structure along the zone of joint.
- 65 19. The method of forming joints in plastic concrete of a road under construction, consisting in pouring the concrete, containing fine and coarse aggregate, and then moving a cleaving implement longitudinally along the line of a joint to separate the coarse aggregate along said line to cause a zone of mortar to accumulate therealong, and thereafter positioning a longitudinal blade in said mortar to form a groove, and then applying suitable aggregate to said mortar to be mixed with said mortar to absorb a portion of the mortar to create a denser structure and thereafter removing the blade to repeat the operation.
- 70 20. The method of forming joints in plastic concrete of a road under construction, consisting in pouring and finishing the concrete, containing fine and coarse aggregate, then separating the coarse aggregate longitudinally along the center of the road in line of a joint and creating a zone of mortar along said line, then positioning a longitudinal blade in the mortar to form a groove, and applying coarse aggregate to be tamped into the mortar to absorb a portion of the mortar and produce a denser structure.

JOHN N. HELTZEL.
